US0D1067890S

(12) **United States Design Patent** (10) **Patent No.:** **US D1,067,890 S**
(45) **Date of Patent:** **** Mar. 25, 2025**

(54) **REMOTE CONTROL PAGE TURNER**

(71) Applicant: **Shenzhen Huazhichuangxing Technology Co., Ltd.**, Shenzhen (CN)

(72) Inventor: **Hengjun Liu**, Linqing (CN)

(73) Assignee: **Shenzhen Huazhichuangxing Technology Co., Ltd.**, Shenzhen (CN)

(**) Term: **15 Years**

(21) Appl. No.: **29/958,364**

(22) Filed: **Aug. 19, 2024**

(51) LOC (15) Cl. **14-03**

(52) U.S. Cl.

USPC **D13/168**

(58) **Field of Classification Search**

USPC D13/158, 162, 164, 168, 173; D14/174, D14/217, 218, 203, 204, 206; D16/219, D16/237, 250; D19/99; D21/332, 405, D21/566

CPC H04N 21/41265; H04N 21/42222; H04N 21/42224; H04N 21/42205; H04N 21/42226; H04N 21/4227; G08C 17/00; G08C 2201/91; G08C 2201/92; G08C 2201/93

(57) **CLAIM**

The ornamental design for a remote control page turner, as shown and described.

DESCRIPTION

FIG. 1 is a top, front and right side perspective view of a remote control page turner, showing my new design; FIG. 2 is a bottom, rear and left side perspective view of therefore;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines show the features of the remote control page turner that form no part of the claimed design.

1 Claim, 8 Drawing Sheets
